Des. 209,526
Patented Dec. 12, 1967

209,526

WHIRLING FLING TOY

Bruce F. Dunbar, 1420 Centennial Drive,
St. Paul, Minn. 55113

Filed Oct. 13, 1966, Ser. No. 4,266

Term of patent 3½ years

(Cl. D34—15)

FIG. 1

FIG. 2

FIG. 1 is a top plan view of a whirling fling toy embodying my new design; and

FIG. 2 is a cross section taken on the line 2—2 of FIG. 1.

I claim:

The ornamental design for a whirling fling toy, as shown.
